US0D1080339S

(12) **United States Design Patent** (10) **Patent No.:** **US D1,080,339 S**
(45) **Date of Patent:** **** Jun. 24, 2025**

(54) **WRENCH DRIVE ROD**

(71) Applicant: **INFAR INDUSTRIAL CO., LTD.**,
Chang-Hua County (TW)

(72) Inventor: **Tai Hung Chen**, Chang-Hua County
(TW)

(73) Assignee: **INFAR INDUSTRIAL CO., LTD.**,
Chang-Hua County (TW)

(**) Term: **15 Years**

(21) Appl. No.: **29/912,534**

(22) Filed: **Sep. 20, 2023**

Related U.S. Application Data

(63) Continuation-in-part of application No. 17/680,549,
filed on Feb. 25, 2022, now abandoned.

(57) **CLAIM**

The ornamental design for a wrench drive rod as shown and described.

DESCRIPTION

FIG. 1 is a perspective view of a wrench drive rod showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the wrench drive rod that form no part of the claimed design.

1 Claim, 7 Drawing Sheets
